James Glenn Fisher, Hartwell, Ga.

Application October 14, 1957, Serial No. 48,085

Term of patent 14 years

(Cl. D55—1)

Fig. 1 is a perspective view of a spooler trough showing my new design; and

Fig. 2 is a perspective view thereof as seen from a slight angle from the right of Fig. 1.

The rear of the vertical portion of the spooler is substantially plain.

The left rear leg as seen in Fig. 1 of the drawing is substantially similar to the right rear leg that is seen in Fig. 2 and projects outwardly from the panel in substantially the same manner as does the right rear leg in Fig. 2.

I claim:

The ornamental design for a spooler trough, as shown and described.
